CLAIM

The ornamental design for an air cleaner cover and engine incorporating the same, as shown and described.

DESCRIPTION

FIG. 1 is a front-right perspective view of an engine according to the new design;

FIG. 2 is a front-left perspective view thereof;

FIG. 3 is a rear-left perspective view thereof;

FIG. 4 is a rear-right perspective view thereof;

FIG. 5 is a front elevation view thereof;

FIG. 6 is a rear elevation view thereof;

FIG. 7 is a right-side elevation view thereof;

FIG. 8 is a left-side elevation view thereof;

FIG. 9 is a top plan view thereof; and,

FIG. 10 is a bottom plan view thereof.

The broken lines show portions of an air cleaner cover and engine incorporating the same which form no part of the claimed design. The broken lines are also for the purpose of showing environmental structure, and form no part of the claimed design.

1 Claim, 10 Drawing Sheets
